LEWIS B. DOMAN, OF ELBRIDGE, NEW YORK, ASSIGNOR TO AMPHION PIANO PLAYER COMPANY, OF ELBRIDGE, NEW YORK, A CORPORATION OF NEW YORK.

GUIDE MECHANISM FOR TRAVELING SHEET

939,897.

Specification of Letters Patent.

Patented Nov. 9, 1909.

Application filed November 10, 1908. Serial No. 461,931.

To all whom it may concern:

Be it known that I, LEWIS B. DOMAN, of Elbridge, in the county of Onondaga, in the State of New York, have invented new and useful Improvements in Guide Mechanism for Traveling Sheets, of which the following, taken in connection with the accompanying drawings, is a full, clear, and exact description.

10 This invention relates to certain improvements in mechanism for maintaining suitable relation between a traveling sheet or web and a tracker bar or other device across or upon which it is adapted to be drawn, 15 wound or unwound and is specially adapted for maintaining normal operative relation between the perforated music sheet and tracker bar of a self-playing musical instrument whereby the perforations of such 20 music sheet may be kept in exact registration with their corresponding ducts of the tracker bar.

The invention in some respects is similar to that set forth in my pending application 25 No. 422,970 filed March 24, 1908, in so far as it makes use of a pneumatically balanced movable member operatively connected to one of the parts between which co-operative 30 relation is desired to be maintained but which is more specifically adapted for sheets or webs of uniform or standard width.

One of the objects of my present invention, as distinguished from that set forth in my pending application referred to, is to enable 35 the device to be adjusted for effective co-operation with music sheets of varying widths, that is either wider or narrower than standard.

Another object is to enable certain portions of the device to be readily adjusted for transposing from one key to another.

Another object is to render the automatic restoration of normal relation between the sheet and tracker bar more responsive to any 45 slight shifting from such normal relation than has heretofore been possible with devices of this character.

Other objects and uses relating to specific parts of the mechanism will be brought out 50 in the following description.

In the drawings—Figure 1 is a front elevation partly in section of a portion of a self-playing musical instrument showing particularly the tracker bar and automatic

shifting mechanism therefor, the music sheet 55 being shown by dotted lines. Fig. 2 is an enlarged top plan partly in section of the tracker bar and an adjustable valve port showing also the guide fingers for the music sheet. Fig. 3 is an enlarged transverse sectional view taken on line 3—3, Fig. 1. Fig. 4 is a top plan of one end of the tracker bar and valve port shown in Fig. 2 showing a slightly modified form of guide finger for the music sheet. Fig. 5 is an enlarged sectional view of one of the vent valves in one of the pipe connections between the valved port and pneumatic regulator.

The device shown in my pending application referred to is particularly effective in 70 maintaining normal relation between the tracker bar and music sheets of standard width but in all such devices in which the sheet or web coats with ducts in the tracker bar or where the automatic maintenance of 75 normal relation between the music sheet and tracker bar is dependent upon the covering or uncovering of certain ducts or ports by the sheet or web, the restoration of relation between the sheet and tracker bar is neces- 80 sarily slow owing to the fact that it is necessary for one of the parts to shift relatively to the other practically the full width of the port or ports before the shifting pneumatic is energized.

In my present invention the slightest deviation of the music sheet or web from its normal line of travel will immediately bring into action the restoring mechanism thereby maintaining a closer normal relation be- 85 tween said sheet and tracker bar.

In carrying out the objects stated I make use of a single regulator pneumatic —1— which in this instance is divided into two compartments —2— and —2'— by a central 95 movable partition —4— which is hinged at one edge and is connected by a link —5— to a tracker bar —6—, the latter being guided in suitable supports —6'—.

A partial vacuum of equal tension is nor- 100 mally maintained in the compartments or chambers —2— and —2'— by connecting said chambers with any suitable exhaust device not necessary to herein illustrate or describe for the reason that these connections may be 105 made directly or indirectly but for the purpose of illustration I have shown the partition —4— as provided with a lengthwise

passage —7— communicating at its inner end through comparatively small apertures —8— with the chambers —2— and —2'—, said passage —7— being connected by a 5 pipe —9— to any exhaust chamber in which a partial vacuum is maintained.

A valve board —10— is associated with and arranged in close proximity to the tracker bar —6— and is provided with atmosphere 10 ports —11— and —11'— which are connected by conduits —12— and —12'— respectively to the chambers or compartments —2— and —2'— of the regulator pneumatic —1— but are normally closed to atmosphere 15 by movable valves —14— and —14'—. These valves are mounted upon movable guide fingers —15— and —15'— which overhang the upper edges of the tracker bar at opposite ends of the series of ducts therein 20 and serve as guides against which the edges of the music sheet or similar traveling web rides during its travel as in playing a musical selection, the distance between the arms corresponding to that of the standard width 25 of music sheet which may be employed. These fingers are preferably tensioned to close the valves —14— and —14'— upon the ports —11— and —11'— by suitable springs —16— and as shown in Fig. 2, said 30 fingers are hinged at their rear ends at —17— to the opposite ends of the valve shelf —10—, the spring —16— being coiled around suitable screws —18— which are passed through apertures in the spring fingers —15— and —15'— and screwed into the adjacent ends of the shelf —10— thereby 35 permitting a slight adjustment of the spring fingers to conform to slightly varying widths of the same or different music sheets 40 which may be employed, the valves being made of slightly compressible material capable of yielding under such adjustment to normally close their respective ports. This adjustment may be materially increased 45 without varying the thickness of the valve by means of the device shown in Fig. 4 in which a valve —14— is secured to an arm —19— similar to but somewhat shorter than the finger —15— and to this arm —19— is 50 secured a spring guide finger —20— tensioned toward the arm —19— and having a threaded aperture in which is movable a screw —21—, the inner end of which abuts against the arm —19— so that by turning 55 the screw —21—, the free end of the guide —20— may be moved laterally or lengthwise of the tracker bar —6— without affecting the position of the arm —19— or valve —14— carried thereby although the entire 60 guide device including the arm —19— and guide finger —20— is tensioned to close the valve —14— by means of a spring —16— and adjusting screw —18— similar to that shown in Fig. 2.

65 The tracker bar —6— and valve shelf

—10— are supported independently of and adjustable relatively to each other for the purpose of transposing the music selection, from one key to another and in order that the operator may intelligently effect this 70 transposition to the desired key I provide the front edge of the shelf with a series of graduations —23— which coact with a pointer —24— on the tracker bar, said shelf being provided with a corresponding number of apertures —26— adapted to receive a locking member or pin —27— which in this 75 instance is rigidly secured to the tracker bar so that when entering one of the perforations as —26— the valve board and tracker 80 bar will be locked together. This adjustment of the valve shelf relative to the tracker bar is effected by simply raising the shelf out of engagement with the pin —27— and moving it longitudinally until the proper 85 aperture corresponding with the key indicated by the graduations —23— and pointer —24— is alined with the pin whereupon the valve shelf is again depressed into interlocking engagement with said pin. I 90 preferably provide two sets of apertures —26— and one pin for each end of the valve port and tracker bar although one set of apertures and locking pin would suffice to effect the desired result. In the present instance this adjustment for transposition is effected before the music sheet is attached to the winding roller either by shifting the valve board by hand relatively to the tracker bar or by shifting the tracker bar relatively 100 to the valve board, which latter operation may be effected by the pneumatic —1— by simply opening one or the other of the ducts or conduits —12— or —12'— to the atmosphere to break the balance of the movable 105 partition —7—, the direction of movement of the tracker bar or valve board depending upon whether the key is to be raised or lowered from that at which such parts are normally adjusted and under which normal 110 conditions the movable partition —7— will automatically restore itself to a position substantially midway between the sides of the pneumatic, whereas in adjusting the valve board and tracker relatively to each 115 other for transposing, such partition will assume a position to one side of the center according to the key above or below the normal key. For example, assume that it is desired to transpose to a key one-half tone 120 above normal key, then the valve board or other connection carrying the valved ports and valves will be shifted to the right one point as indicated by the graduations —23— and pointer —24— corresponding to the distance 125 between the ducts of the tracker bar whereupon the music sheet is drawn between the guide fingers —15— and attached to the winding roller, not shown, so that when the music sheet is straightened, its left hand 130

edge which is in contact with the adjacent guide finger, will straighten out and open the left hand valve —14— thereby opening the compartment or chamber —2— to the atmosphere which breaks the equality of tension in the compartments —2— and —2'— and causes the movable partition —7— to be drawn to the left hand side of the pneumatic by reason of the minus pressure therein, it being understood that under such conditions the right hand valve remains closed. This shifting of the partition —7— causes a similar shifting movement of the tracker bar and valves connected thereto until the left hand valve is again closed. The partition —7— remains in its shifted position during such adjustment for transposition unless the music sheet should deviate from its normal line of travel under which conditions one or the other of the valves —15— or —15'— would be opened according to the direction of shift and cause the partition —7— to again slightly shift to restore normal relation between the music sheet and tracker bar, such relation being automatically maintained in the transposing adjustment, the same as previously described for normal pitch. Or instead of shifting the valve support relatively to the tracker bar for transposition, the left hand valve may be opened by hand by simply pressing the finger against the guide —15— in which case the pneumatic —7— will be actuated to shift the tracker bar one or more points as may be desired, it being understood that during such shift of the tracker bar the valve board will simply be elevated out of engagement with the locking pin —27— until the desired adjustment is effected whereupon the valve board will be reengaged with such locking pin to hold the valve ports and valves in fixed relation to the tracker bar to shift therewith for automatically obtaining normal relation between the tracker bar and music sheet.

The same effect as last described, however, may be produced by providing the ducts —12— and —12'— with suitable valves —28— having finger pieces —29— by which such valves may be opened to atmosphere allowing atmospheric air to enter one of the chambers —2— or —2'— thereby causing the action of the partition —4— to shift the tracker bar in the manner previously described.

The specific valve board and locking means between it and the tracker bar are shown only for the purpose of illustrating a simple means for carrying out the objects of my invention but it is to be understood that any means whereby the valve ports and valves may be locked to shift with the tracker bar is within the scope of my present invention, the feature of adjustment of the valve ports and valves being merely for transpos-

ing from one key to another or for raising or lowering the pitch from normal as may be desired.

The principal feature of the invention lies in providing valve ports with movable valves which are connected to and adapted to be operated by guide fingers engaging the edges of the sheet and controlling the operation of a pneumatic by which normal relation between the tracker bar and music sheet is maintained or restored when such relation is abnormal, as distinguished from ports in the tracker bar which are normally covered by the web or music sheet in which latter case any ragged or imperfect edge of such sheet would prematurely uncover the adjacent port and cause consequent shifting of the tracker bar out of registration with the perforations in the sheet. In my present device such ragged or imperfect edge of the music sheet would have no effect upon the valve which would remain closed unless actually opened by the lateral shifting of either the sheet or tracker bar.

The valves —28— and —29— constitute separate manually controlled pneumatic means for shifting the tracker bar, as for instance from one key to another and may be located in any convenient position upon the piano case, preferably on the front board directly in front of the keys where they are readily accessible to the operator although I have not deemed it necessary to show any particular location for these valves in the present instance as it is well understood that they will be located in some position within easy reaching distance of the operator during the playing of a musical selection. This manually controlled pneumatic means for shifting the tracker bar, as, for example, to transpose from one key to another key is more fully set forth and claimed in my pending application No. 490,796, filed April 19th, 1909.

What I claim is:

1. The combination with a traveling music sheet and tracker bar, of a valve support movable relatively to the tracker bar and provided with valve ports, valves for said ports, operating members for said valves engaging opposite edges of the sheet, and a pneumatic controlled by said valves for maintaining normal relation between the music sheet and tracker bar.

2. The combination with a traveling music sheet and tracker bar, of a valve support movable relatively to the tracker bar and provided with valve ports, valves for said ports, operating members for said valves engaging opposite edges of the sheet, a pneumatic controlled by said valves for maintaining normal relation between the music sheet and tracker bar, and means for locking the valve board to the tracker bar.

3. The combination with a traveling sheet

and movable tracker bar, of means for maintaining normal relation between the sheet and tracker bar comprising a movable member normally balanced under equal air tension and controlling the movement of the tracker bar, separate air ports communicating with opposite sides of said member, separate normally closed valves for said ports, guide fingers for the edges of the music sheet movable with and independently of the tracker bar and controlling the opening of said valves to vary the air tension at the side of the movable member communicating with the opened port and thereby causing the movement of the tracker bar for restoring normal relation between the music sheet and tracker bar.

4. In combination with a traveling sheet or web, a movable tracker bar, a movable member normally balanced under equal air tension and controlling the movement of the tracker bar, separate normally closed air ports communicating with opposite sides of said movable member, separate devices, including guide fingers movable with the tracker bar and engaging the edges of the music sheet and operable by the disturbance of normal relation between the music sheet and tracker bar to open one of said ports and thereby vary the air tension at the side of the movable member which communicates with such opened port, one at least of said fingers being adjustable toward and from the other, and means for effecting such adjustment.

5. In combination with a tracker and music sheet of a pneumatic self-playing musical instrument, a pneumatic having separate compartments and an interposed movable partition between the compartments, separate conduits leading from the compartments, manually operated valves connected to said conduits and adapted to be opened to the atmosphere to admit the latter to one or the other of the compartments for actuating the partition, and connections between the partition and tracker for shifting the latter relatively to the music sheet.

6. In a guide mechanism for traveling sheets, a tracker, air compartments in which an equal air tension is normally maintained, separate air ports each communicating with one of said compartments, valves for said ports, guide fingers for the edges of the music sheet and connected to their respective valves and adapted to be moved by the shifting of the music sheet to open one or the other of the ports and thereby vary the air tension in the corresponding compartment, and means actuated by the inequality of the air tension in said compartments for shifting the tracker and guide fingers to restore normal relation between the sheet and tracker.

In witness whereof I have hereunto set my hand this 6 day of November 1908.

LEWIS B. DOMAN.
